UNITED STATES PATENT OFFICE.

GEORG BUHLMANN, OF BERLIN, GERMANY.

PROCESS OF MANUFACTURING INCANDESCENT MANTLES.

SPECIFICATION forming part of Letters Patent No. 698,102, dated April 22, 1902.

Application filed June 29, 1901. Serial No. 66,583. (No specimens.)

To all whom it may concern:

Be it known that I, GEORG BUHLMANN, manufacturer, a subject of the King of Prussia, German Emperor, and a resident of 55^b 5 Koepenicker street, Berlin, in the Kingdom of Prussia, German Empire, have invented a new and useful Process of Manufacturing Incandescent Mantles, of which the following is an exact specification.

10 My invention relates to a process for manufacturing incandescent mantles, and has especially for its purpose to provide a process by means of which the mantles are at the same time reduced to ashes and brought in proper shape, which two operations have to be effected separately in the processes known up to date. It has been tried already to burn the mantles upon refractory cores in muffle-furnaces or in muffles in one operation; but 15 20 25 30 35 40 45

this process has proved in practice to be very unpractical and expensive. This process has, further, the disadvantage that by the slow decomposition of the nitrates the luminous effect of the mantles is considerably reduced. Therefore this process has practically not been used at all, the only process used consisting in first reducing the impregnated mantle to ashes and then exposing the shrunken mantle to a flame directed radially toward the outside in order to bring the same into proper shape. In exposing the mantle to the flame either the mantle or the burner had to be moved upward and downward in order to expose gradually the whole mantle to the flame. This process depends greatly upon the skill of the workman and has the great disadvantage that always only part of the mantle is heated and herewith gets a greater elasticity, whereby it is attained that a dislocation of the elastic parts in regard to the other parts of the mantle takes place, by means of which dislocation the structure of the mantle gets loose and tensions or the like irregularities in the pseudomorphose of the oxids arise. These disadvantages are done away with by the object of the present invention.

The process consists in placing the impregnated mantle around a wire webbing the 50 form of which corresponds to the desired form of the mantle, whereby the diameter of the wire-webbing mantle is a little bit smaller

than the diameter of the mantle to be manufactured. Now a mixture of gas and air is led with a certain velocity into the interior 55 of the wire-webbing mantle, whereafter the mixture is lighted on the outside of the mantle, so that a burning cover is formed around this wire-webbing mantle. This burning cover serves for reducing the mantle to ashes 60 and at the same time for bringing the same into its proper shape. The impregnated mantle is at first reduced to ashes with great rapidity by means of the heat produced by the burning cover and by its being reduced to 65 ashes shrinks together until it reaches the burning cover. In this position the glowing proper of the mantle takes place, whereby the mantle adopts without any manual help the shape of the wire-webbing mantle. 70

The process may also be carried into effect by bringing a burning flame into the wire-webbing or the like mantle by which flame the whole mantle begins to glow, which glowing may also be caused by any other heating 75 source. In this case a very hot air-mantle will be formed around the metal mantle, which hot air influences the impregnated mantle in the same way as the burning cover mentioned above. 80

In the accompanying drawings the process is illustrated in its different states.

Figure 1 shows the apparatus for carrying the same into effect in a small scale. The apparatus consists of a burner-pipe A, to which gas is led through the pipe B. To the pipe A a blowpipe C is fixed, which is connected with an air-pipe C. To the upper edge of the burner-pipe A a wire sieve-body D is attached, which sieve-body may be shorter than 85 the mantle to be burned is before the burning of the same. The sieve-body D is shown in Figs. 2, 3, and 4 in its original size. 90

Fig. 2 shows the sieve-body D with the rough, impregnated, and unburned mantle E. 95

Fig. 3 shows the burning and the simultaneously contracting and shrinking of the mantle. F is the layer of flames, which forms around the sieve-body D.

Fig. 4 shows the mantle ready for being 100 taken off.

The special advantages of the process consist especially in the mantles being perfectly alike in form, which never could be attained

by the processes used up to date. At the same time the losses arising by the cracking of the mantles and the bad shapes of the same are reduced to a minimum by the new 5 process of treating the same, by means of which process it is attained that the treating of the mantles no more depends upon the skill of the workmen. Furthermore, the process goes on much quicker than the processes known up to date, especially the transformation of the impregnated mantle into the pseudomorphose of the oxids, which transformation lasts only a few seconds, while, for instance, when carried into effect by 10 means of burning the mantles in muffles this process lasts about twenty-four hours.

Having thus fully described the nature of this invention, what I desire to secure by Letters Patent of the United States is—

A process of manufacturing incandescent 20 mantles, consisting in exposing the impregnated mantle to a flame, produced around the outer surface of a sieve-body, corresponding in form and size to the desired form of the mantle, substantially as set forth. 25

In testimony whereof I have signed my name to this specification in the presence of two subscribing witnesses.

GEORG BUHLMANN.
